UNITED STATES PATENT OFFICE.

SAMUEL SEABURY, OF THE UNITED STATES NAVY.

GAS-CHECK FOR BREECH-LOADING ORDNANCE.

SPECIFICATION forming part of Letters Patent No. 487,380, dated December 6, 1892.

Application filed August 3, 1892. Serial No. 442,054. (No model.)

To all whom it may concern:

Be it known that I, SAMUEL SEABURY, lieutenant in the United States Navy, at present residing at Bayonne, in the county of Hudson and State of New Jersey, have invented a new and useful Improvement in Gas-Checks for Breech-Loading Ordnance, of which the following is a specification.

This invention is applicable to that class of breech-loading ordnance in which the removable breech-block is inserted into and withdrawn from the gun by movements in line with the bore or parallel with the axis thereof, and is also applicable to that class in which the breech is opened and closed by a movement of the breech-block transverse to the bore.

The object of the improvement is to obtain a gas-check which shall not only be simple in construction and efficient in action, but shall be, also, entirely free from liability to stick or bind and to thereby impair the freedom of the necessary movements of the breech-block.

Figure 1 represents an axial section of the breech portion of a cannon having a mutilated screw-threaded breech-block which is inserted into and withdrawn from the breech by movements parallel with the bore, illustrating the application of my invention to a cannon of that class. Fig. 2 represents a similar section, on a larger scale, of some of the parts shown in Fig. 1. Fig. 3 is a view corresponding with Fig. 2, illustrating a modification of my invention as applied to the same class of guns. Fig. 4 represents an axial section in a horizontal direction of the breech portion of a cannon having a transversely-sliding breech-block.

Similar letters of reference designate corresponding parts in all the figures.

I will first describe my invention with reference to Figs. 1 and 2.

A designates the body of the cannon, bored through the breech and counterbored and screw-threaded to receive the breech-block B, which is constructed and fitted in a manner common to cannon having such breech-blocks, except that the face of the said block and the seat provided in the breech of the gun for said block are made of a circumference somewhat larger than the bore *a* of the chamber of

the gun to provide for the reception of my improved gas-check.

C *n* designate the gas-check, which in 55 this example of my invention is composed of a circular disk C of metal, preferably of steel and elastic, a flanged steel collar J, fitted to a central opening in said disk, and a packing-ring or gasket *n*, the said collar and disk being attached to the breech-block by a bolt D, passing centrally through the said block and through the said collar. The flange *q* around the front of the said collar J lies and bears against the front of the disk C, and the part 60 of the collar behind the said flange projecting through the back of the disk C is fitted to a counterbore *r*, provided in the face of the breech-block in front of the central bore, which is provided through the said block for 65 the bolt D. The bolt D has a shoulder which abuts against the back of the counterbore *r* and is held rigidly in place by means of a nut *d*, fitted to a screw-thread provided on its rear part. The said bolt is represented as having 70 a central bore to constitute the vent for firing and its rear end counterbored, as shown at *e*, to receive a primer.

The disk C is of a circumference not less than that of the face of the breech-block, and 80 consequently larger than that of the bore of the chamber of the gun, in order that its marginal portion may overlap the bore and be received between the marginal portion of the face of the breech-block and the 85 face *s* of the front part of the screw-threaded breech-block seat surrounding the bore. A space *t* is provided in the breech-block seat around the forward portion of the breech-block and the outer circumference of the 90 disk C. The said disk C is represented as 95 substantially flat, except in the marginal portion which is received between the face of the breech-block and the face *s* of the breech-block seat, which portion has an annular rearward bulge to form an annular groove in its face for the reception of the packing-ring or 100 annular gasket *n*, a corresponding groove being formed in the face *s* for the reception of the said ring or gasket. The marginal portion of the face of the breech-block is hollowed out to conform to the marginal portion of the back of the disk C. The portion of the face of the breech-block which is oppo-

site the bore a' of the gun and opposite the flat portion of the disk C is slightly dished or concave, as indicated at c' in Figs. 1 and 2, to permit the backward bulging of the said portion of the said disk when it is subjected to the pressure produced upon its face by the firing of the gun.

The ring or gasket n may be made of any suitable elastic or plastic material; but I prefer to make it of a composition of asbestos and grease, such as is now commonly used in some of the gas-checks for breech-loading ordnance. The said ring, which may be of round or square transverse section, may be attached to the face of the disk or placed in the groove in the face s of the breech-block seat. When the breech-block is screwed up after loading, the said ring or gasket and the marginal portion of the disk will be tightly clamped between the breech-block and the face s of the breech-block seat, and when the gun is fired the pressure will act upon the flanged collar J and the portion of the disk outside of said collar to press back into the cavity c' of the breech-block the portion of the said disk opposite the said cavity. The disk will then assume the character of an annular lever, the fulcrum xx of which is the circular edge formed around the cavity c' in the breech-block, and by this lever-like action the marginal portion of the disk outside of the said edge will be pressed forward and caused to compress the gasket or packing-ring so tightly between the breech-block and the face s of the breech-block seat as to preclude the possibility of any leakage of gas. After the discharge of the gun the elasticity of the disk produces the return of the flanged collar J to the normal condition. (Shown in Figs. 1 and 2.)

In order to prevent any leakage of gas between the flanged collar J and the bolt D, a groove v is so turned in the face of the said collar as to form a very thin and flexible annular lip z , Figs. 2 and 3, around the said bolt. Any gas getting between the head of the bolt and the said flange entering the said groove produces such contraction of the edge of the said lip around the bolt as to form a gas-tight joint.

The example of my invention illustrated in Fig. 3 differs from that shown in Figs. 1 and 2 in having no packing-ring or gasket. In this example the metal disk C is represented as flat all the way to its circumference, but is in other respects like the first example. Its marginal portion is, as in the first example, screwed up between the face of the breech-block and the face s of the seat. The lever-like action of the said disk, above described as produced by the pressure of gases, forces the face of the marginal portion of the said disk hard and tight against the face s and tends to produce a gas-tight joint between them.

In the example shown in Fig. 4 with the transversely sliding breech-block the central

portion of the disk C is cupped to receive within it the collar J and the head of the bolt D, and the said block is counterbored from its face around the bore provided for the said bolt to receive the said cup, so that the said bolt-head and collar are so countersunk within the breech-block as not to interfere with its sliding movement. In this example the packing-ring or gasket n is square in its transverse section and is received and retained within a groove of corresponding form in the front of the breech-block seat, and the marginal portion of the disk is flat; but the same lever-like action described with reference to Figs. 1 and 2 occurs when the pressure of the gases acts upon the disk and the marginal portion of the disk is made to compress the gasket or packing-ring n and to make a tight joint between the breech-block and the bore. In adapting my invention to the sliding breech-block the packing-ring or gasket may sometimes be dispensed with and the margin of the disk may operate in direct contact with the face s or front of the breech-block seat, as it does in the example Fig. 3.

What I claim as my invention, and desire to secure by Letters Patent, is—

1. The combination, substantially as herein described, of a breech-loading gun, a breech-block therefor having a portion of its face concave, and a gas-check disk, the marginal portion of which disk, adapted to overlap the bore of the gun, is received between the front face of the breech-block seat and the marginal portion of the face of the breech-block and the other portion of which disk nearer to its center is free to move backward within the concave of the breech-block face for the purpose of exerting a forward pressure on its marginal portion, as herein set forth.

2. The combination, substantially as herein described, with a breech-loading gun and a breech-block therefor having a portion of its face concave, of a disk C and a flanged collar J, fitted to a central opening in said disk, and a central bolt for attaching said disk and collar to the breech-block, the said disk being adapted to overlap the bore of the gun and to be received between the face of the breech-block and the front face of the breech-block seat and the collar and the central portion of said disk being free to move backward on said bolt, for the purpose herein set forth.

3. The combination, with the breech-block, of a gas-check disk, a central bolt for attaching said disk to the face of the breech-block, and a collar fitted to said bolt to bear against the front of the disk and constructed with a flexible lip z to prevent the escape of gas around said bolt, substantially as herein set forth.

SAMUEL SEABURY.
